VOTING MACHINE TO FACILITATE
STRAIGHT TICKET VOTINGRansom F. Shoup, Ardmore, Pa., assignor to The
Shoup Voting Machine Corporation, Philadelphia, Pa., a corporation of Delaware

Application January 7, 1949, Serial No. 69,674

12 Claims. (Cl. 235—55)

1

This invention relates to voting machines and more especially to voting machines of the type disclosed in Shoup Patent No. 2,054,102.

In this type of voting machine, there are several vertical columns of voting spindles in combination with an interlock that can be arranged to prevent actuation of more than a selected number of spindles in any horizontal row or vertical column. Also for each horizontal row of spindles, there is a slot through which a personal choice may be written in, such slot being normally closed by a slide termed a personal choice slide. Each personal choice slide also is capable of being connected to the interlock in such a manner that the opening of selected personal choice slides prevents actuation of selected individual voting spindles beyond a limited number until after the machine has completed its vote registering operation.

In some jurisdictions, at a primary general election of county, state or national officials, there is also an election of a large number of local officers such as ward committeemen. Likewise in the case of presidential primary elections delegates at large and alternates in large numbers are to be selected. Generally in such cases each party presents several groups, for example, of ward committeemen, delegates, delegates at large, and alternates. Each party voter has the privilege of selecting any one of the groups of his party and voting a straight ticket for the selected group, or of voting individually for candidates in the various groups presented by his party, or else has the privilege of splitting his vote among candidates named in the various groups and exercising personal choice options, or else has the privileges of exercising personal choice options entirely all to the limit of the number of candidates permitted his party for the offices in question.

A principal feature and object of this invention is to provide mechanism applicable to voting machines extant and of the character described that will enable a portion thereof to be set up to meet these requirements.

A further principal feature and object of the invention is to provide mechanism of this kind that is comparatively simple in construction and readily applicable to such voting machines without the necessity of material alteration thereof and which will comply with statutes governing such types of election.

It is another object and feature of this invention to provide simple mechanism applicable to voting machines extant and of the character de-

scribed that will enable a portion or portions thereof to be set up to meet requirements of selective primary elections as will hereinafter be explained.

5 It is another object and feature of the invention to provide simple mechanisms applicable to voting machines extant and of the character described that will enable a portion or portions thereof to be set up to meet requirements of declared primary elections as will hereinafter be explained.

Other objects, novel features and advantages of this invention will become apparent from the following specification and accompanying drawings, wherein:

Fig. 1 is a fragmentary front view of the voting machine illustrating the manner in which it is set up for the selection of a large group of officers, such as ward committeemen;

20 Fig. 2 is a fragmentary rear view of the frame of the voting machine showing the position of parts as the voter enters the machine;

Fig. 2a shows in elevation exploded views, on an enlarged scale of details of the mechanism involved;

25 Fig. 3 is a fragmentary rear view of the frame of the voting machine showing the position of parts when the voter has operated a straight ticket selecting lever to select all of the group of his party's candidates in one of the vertical columns of the machine;

Fig. 4 is a similar fragmentary view illustrating positions of parts when the voter has elected to split his vote and vote for individuals rather than vote a straight ticket for an entire named group of his party's candidates;

30 Fig. 5 is a fragmentary section taken along line 5—5 of Fig. 2 and viewed in the direction of the arrows;

40 Fig. 5a is a perspective view on an enlarged scale of a detail of the mechanism involved;

Fig. 6 is a fragmentary rear view of a modified form of construction;

Fig. 7 is a fragmentary section taken along line 7—7 of Fig. 6;

45 Fig. 8 is a fragmentary rear view of a voting machine illustrating use of features of the invention in selective primary elections; and

Fig. 9 is a fragmentary rear view of a voting machine illustrating use of features of the invention in declared primary elections.

In so far as practical, the reference characters used herein will correspond to the reference characters used in the specification of Shoup Voting

Machine patents such, for example, as Shoup et al. No. 2,054,102 and Shoup No. 2,191,086.

In the voting machine of Shoup et al. Patent No. 2,054,102, there are ten vertical columns of spindles, a personal choice column of slides for write-in votes, and a main interlock together with interlock straps for connecting to the main interlock both the spindles of columns one to nine, counting away from the interlock, and, also, parts associated with slides in the personal choice column. Fig. 1 herein shows only nine of the columns and the personal choice column. Fig. 2 herein shows all ten columns but not the personal choice column, while Figs. 3-6 inclusive show fewer of the columns, all counting away from the interlock. The interlock straps for the spindles of as many of the columns as are to be used in voting of the character to be described and for the personal choice slides are preferably of the type shown and described in Shoup Patent No. 2,191,086 or Shoup Patents 2,251,254 and 2,251,255.

Referring particularly to Fig. 5, the spindles 38 are journaled at one end in a plate 39 and at the other end are journaled in vertical straps 40. Each spindle is equipped with an operating handle 30 and is of square cross section except that it is provided with a circular groove 38a to be received in a circular bearing provided therefor in straps 40, and with additional similar circular grooves 38b for other purposes. Each spindle 38 extends through and supports a channel member 60, the ends of which engage the plate 39 and a strap 40 and the channel member 60 is received within square apertures in two arms 59 and 59'. The plate 59a is attached to each arm 59' through the intermediary of the rod 59b which passes through a hole in the arm 59' and a slot in the plate 59a. The plate 59a is thus slidably and rotatably connected to the arm 59' and is, therefore, capable of being adjusted to different positions relative to the arm as fully described in said Patent 2,191,086. By reason of the rectangular cross section of the channel member 60 and its snug fit on the square portion of the spindle 38, it is firmly secured to the spindle for rotation therewith. Likewise, rotation of the said spindle 38 causes rotation of the arms 59 and 59'. The arms 59 cooperate with their reclosing frame 65 as described in said Patent No. 2,054,102 and the arms 59' and plates 59a cooperate with vertically and horizontally movable members (not shown) and straight ticket voting handles (not shown) in the manner described in said Shoup Patent No. 2,191,086.

A counter C is associated with each spindle 38 and is provided with a drive pinion 43 having a square aperture through which extends the square portion of the spindle 38. The counter C preferably is of construction described and claimed in the Shoup Patent No. 2,140,336.

Each rod 59b has connected therewith, one end of an interlock or pull strap 61 leading to a main interlock 42 of a construction described and claimed in Shoup Patent 2,191,086. In this interlock 42 are provided a plurality of interlock members 62, certain of which are tubular for the purpose of receiving pins 63 extending through apertures in the interlock casing for the purpose of fastening said members against movement relative to the casing of said interlock 42. Each interlock strap passes between a pair of interlock members 62 and is provided with a wedge 64 for spreading the two members apart.

In the wall 10, there is provided a vertical column of personal choice slots 139 with a slidable

closure 140 for each slot. One of such slots 139 is aligned with each of the horizontal rows of spindles 38. In back of the slots 139 is a guide table 141 over which passes a sheet of paper 142 from a feed roller 143 to a take-up roller (not shown). A yoke 150 pivotally supported on a vertical rod 150a is rotated counterclockwise from the position shown in Fig. 5 by movement of any closure 140 to its open position and when actuated is returned to its original position upon return of the machine to curtain open position by means (not shown but fully disclosed in said Shoup Patent No. 2,054,102). The yoke 150 cooperates with mechanism (not shown) to advance the strip 142 a predetermined distance for each actuation of the yoke.

The rod 150a is supported by brackets 150b attached to a vertical plate 150c in the shape shown in Fig. 5, and the plate 150c is provided with a vertical series of apertures constituting guideways for links 161 which at one end are attached to arms 160 pivotally supported by the rod 150a and each link is provided with a pin 61a connected to an interlock strap 61. Each of the arms 160 is provided with a head 160' projecting into a slotted channel-shaped runner 222 having a right angle extension attached to a slide 223 supported by the wall 10. Each slide 223 is in alignment with a personal choice slot closure 140 so that movement of a personal choice slot closure into open position swings the arm 160 counterclockwise with consequent leftward movement of the corresponding link 161 and its associated interlock strap 61 to bring the wedge thereof between the rollers 62. Restoration of any actuated arm 160 and corresponding closure 140 is effected by mechanism for that purpose described in the Shoup et al. Patent No. 2,191,086.

On each spindle 38 is located an arm or butterfly B consisting of two plates 81 and 82 having square apertures of proper size snugly to receive the square portion of a spindle 38 and the apertures are so arranged that they register with each other only when the plates 81 and 82 are oriented with respect to each other and are out of register when the arms coincide so that they can be locked in desired positions on a spindle 38. These arms forming the butterfly B are more particularly described in the copending Shoup application Ser. No. 14,713 filed March 13, 1948, issued January 31, 1950, as Patent Number 2,496,106. A stud or finger 85 extends from the butterfly B in a direction parallel with the spindle axes. This stud 85, as described in the last-named application, operates to lock the two plates 81 and 82 together and for other purposes presently to appear.

To satisfy the requirements of specific laws relative to voting of the character described, selected of the individual spindles 38 in various of the columns used must be so controlled that a voter can utilize them to vote a straight ticket for all the members of a large group in the column or columns and positions thereof allotted to his party. He must also be able to utilize others of the individual spindles 38 to vote only for particular candidates named by his party in the said large group to the limit of the number of candidates allotted to his party. Also he must be able to split his ticket and vote for party-named candidates and personal choice candidates, all to the limit of the number of candidates allotted to his party in said large group, or else be able to vote all personal choice candidates in lieu of named party candidates in said large groups to the limit

of the number of candidates allotted to his party in said group. These various ways of voting must be mutually exclusive so that if one manner of voting is selected by the voter and his vote set up on the voting machine he cannot vote in any of the other ways unless before leaving the booth he resets various of the spindles 38 he has operated to such a condition as will restore the counters C associated with operation of the spindles 38 to an unvoted condition. The mechanism now to be described satisfies all of these requirements.

The mechanism for voting of the character described includes horizontally disposed members or plates 605 having lateral upper and lower flanges 605a and 605b and a length sufficient to span the number of voting columns it is to control. In the embodiment shown, three such plates 605 are shown and each has a length sufficient to span all the columns of the voting machine. The plates 605 may, however, be of any desired length so as to span as many columns as are to be used. The three plates are interconnected to be movable as a unit, for example, by the locking pins or members 606 extending between adjacent pairs of the flanges 605a and 605b. If desired, fewer or more plates 605 than three may be used and their widths may be as necessary and desirable for particular voting conditions. Each plate 605 is provided with vertically arranged columns of generally rectangular apertures 607 so that a spindle 38 may pass through each aperture. The left wall 608 of each aperture as seen in Fig. 2 has an arcuate recess 609 at the bottom thereof. Each aperture 607 also receives the pin or stud 85 associated with the butterfly B of the spindle 38 passing through said aperture. The function of the particular shape of the apertures 607 is as described in copending Shoup application, Serial No. 30,693, filed June 2, 1948, issued February 21, 1950, as Patent Number 2,498,380. Other types of apertures may, also, be used. The vertically arranged columns of the apertures 607 of the interconnected plates 605 are aligned and the number thereof in each vertical column is as necessary for particular voting conditions.

The plates 605 are retained in longitudinally slidable position upon selected spindles 38 of selected horizontal rows of such spindles and are guided horizontally by appropriate retaining members. The latter, for example, in the embodiment shown consists of strips 610. These strips have holes 611 spaced apart distances corresponding to those of the spindles 38 so that the strips may be mounted over appropriate spindles 38 into abutment with the edges of flanges 605a, 605b. These strips 610 are prevented from sliding off the spindles by locking members 612. Each of these locking members has an opening 613 through which the square sections of spindles 38 may pass freely and a portion 614 shaped to fit into annular recesses 38b in any of the spindles 38. A second recess 615 similar in shape to recess portion 614 is provided on the lower edge of member 612. The spacing between recesses 614 and 615 is equal to the vertical distance between any two spindles 38 in a vertical column. Members 612 are slid onto the uppermost of a pair of spindles 38 straddled by a member 610 and then moved downwardly to cause the recesses 614 and 615 to engage in the corresponding recesses 38b in the respective pair of spindles 38. These members 612 are then fixed in place by bolts or studs 616 that are inserted through holes 617 in members 612 and screwed into threaded holes 618 provided in the member or strip 610. The normal

position of the spindles 38 is such that when the locking members 612 are fixed in place on any pair thereof as just described the recesses 614 and 615 engage in recesses 38b of the spindles 38 involved and cannot slide off. The strips 610 have laterally bent flanges 610a and 610b that respectively overlie a flange 605b and underlie a flange 605a of plates 605. Two or more strips 610 and locking members 612 are used on spindles 38 of various of the vertical columns and horizontal rows of spindles 38 involved and their bent over flanges 610a, 610b provide horizontal guides for the flanges 605b, 605a of plates 605 preventing upward or downward movement of the latter, while the edges of flanges 605b, 605a of plates 605 abut the rear faces of the strips 610 and prevent their movement forwardly. Butterflies B behind the plates 605 prevent movement rearwardly of the plates 605 on the spindles 38 involved. Other equivalent means for effecting this result may be employed. A biasing spring 620 whose ends 621, 622 are secured respectively to a stud 616a screwed into one of the holes 618 of one of the strips 610 and to a stud 623 projecting from one of said plates 605 acts to bias the plates 605 toward the right of Fig. 2. Other biasing arrangements may be used that will accomplish the same result.

An angle bracket 630 is secured to the flange 605a of the uppermost of the plates 605. The upright part 631 of this bracket extends upwardly so that its upper edge lies in the path of travel of the studs 85r on the butterflies Br of the horizontal row of spindles 38r just above the uppermost horizontal row of such spindles 38 that is straddled by the plate or plates 605a. The bracket 630 in the embodiment shown in Fig. 2 has a length spanning ten columns of spindles 38. It may, however, be of any desired length to span only as many columns as may be necessary. Equally spaced-apart recesses 633 are provided in the upper edge of arm 631. Each of these recesses 633 has an arcuate wall 633b and a straight wall 633a. The recesses 633 are positioned so that, in the normal position of the plates 605 under action of biasing spring 620 and with the spindles 38r of the group of spindles in question in unvoted condition, a recess 633 lies in the path of travel of each of studs 85r on the butterflies Br of the respective spindles 38r in the row r of spindles directly above the uppermost flange 605a. When any one of this row of spindles 38r is actuated by operation of its voting handle 30r to a voting position, the stud 85r of the actuated spindle 38r enters the recess 633 registering therewith and acts with the arcuate wall 633b thereof to lock the plates 605 in the condition in Figs. 2 and 3. This locking action, on plates 605 locks out all or selected of the spindles 38 in the horizontal rows of spindles 38 below row r straddled by the apertures 607 of the plate 605 for purposes presently to be described. This horizontal row r of spindles 38r is termed hereafter the straight ticket row of voting spindles.

The spindles 38r of this straight ticket row r of voting spindles all have their interlock straps 61r connected in a portion 42r of the main interlock 42 that is set up for a vote one condition. Thus actuation of any one of these straight ticket row spindles 38r precludes actuation of any others of them. The interlock straps 61r of this straight ticket row r of spindles could, of course, be connected in a portion of the main interlock 42 set up to a vote two or a vote three or other desirable

condition depending upon the number of candidates in the group allotted to the voter's party.

Assume for the purposes of illustration that the straight ticket horizontal row r of spindles is the one whose voting handles $30r$ lie in the horizontal row r of Figs. 1 to 4 inclusive. These spindles $38r$ of this row furthermore are assumed to have their interlock straps $61r$ connected in a vote one condition interlock $42r$. Assume, furthermore, that party D has presented two groups of ten candidates each, while party R has presented four groups of ten candidates. Party D's two groups of candidates in Figs. 1 and 2 are shown set up in the first and second vertical columns of spindles 38 counting away from the main interlock, while party R's four groups of candidates are shown set up in the 4th, 5th, 6th and 7th vertical columns of spindles 38 . The ten individual candidates named in each group appear respectively aligned with an individual voting lever 30 in these vertical columns in the ten horizontal rows of spindles 38 directly below the straight ticket voting row r . The plate 605 is positioned as seen in Fig. 2 so that an aperture 607 straddles each spindle 38 in all ten of said horizontal rows of spindles 38 .

In the normal position of parts as the voter enters the booth, all spindles 38 of the said ten horizontal rows, all spindles $38r$ of the straight ticket voting row of spindles and all individual voting levers 38 and $38r$ are in the unvoted condition shown in Figs. 1 and 2. In fact all voting spindles and voting levers of the entire machine are in such unvoted condition. The plates 605 are then biased under action of spring 620 to the right of Fig. 2 so that the studs 85 of the butterflies B of spindles of said ten horizontal rows lie in the arcuate recesses 609 of respective straddling apertures 607 . At the same time the respective recesses 633 underlie the studs $85r$ of the butterflies Br. As soon as the voter enters the booth and closes the curtain and decides to vote a straight ticket for the ten candidates named in group II of party D's candidates, he operates voting lever $30r$ adjacent group II of column 2 in straight ticket row r to a voting position. As seen in Fig. 3, the particular spindle $38r$ thus actuated rotates butterfly Br thereof from the substantially horizontal position shown in Fig. 2 to substantially the vertical position of Fig. 3. Its stud $85r$ then lies against the straight portion $633a$ of recess 633 which it has entered. The arcuate portions $633b$ of the particular recess 633 entered (as well as all such arcuate portions $633b$ of all recesses 633) has a center of curvature and radius that is sufficient to permit entry of the particular stud $85r$ upon the rotation of the actuated spindle $38r$ to its voting condition. The arcuate portions $633b$ preclude any longitudinal shift of the plates 605 as soon as a stud $85r$ has entered any one of said recesses 633 and been moved into the voting condition of its butterfly Br. This particular arcuate portion $633b$ entered acts in this manner because the plates 605 are prevented from upward and downward movement by the guiding members 610 as previously described. In consequence, the plate 605 is locked against horizontal movement as soon as any one of studs $85r$ has been moved to a voting position. In the case shown in Fig. 3, it is the stud $85r$ of the second vertical column of spindles that has effected this locking action. The resulting locking of plates 605 acts to lock out all ten horizontal rows of spindles 38 below row r because the studs 85 of

the said ten rows lie in their respective arcuate recesses 609 . In consequence, the voter is precluded from operating any individual candidate's name in any of the said ten horizontal rows below row r . Likewise, since the interlock straps $61r$ of the row r spindles $38r$ are connected to a vote one condition interlock $42r$, no others of the voting handles $30r$ may be actuated to a voting position.

Should the same voter decide instead to split his vote among the two groups of his party D instead of operating any of the voting handles $30r$, he will operate voting handles 30 in either of the columns 1 and 2 under groups I and II of party D. As soon as any one of such voting handles 30 is moved to a voting position, the butterfly B of its associated spindle is moved to a voting position. This causes the stud 85 thereof to move out of recess 609 of its straddling aperture 607 against the biasing action of spring 620 and onto the straight portion 608 of said aperture. In such movement, a longitudinal shift of all plates 605 is effected toward the left of Figs. 2, 3 and 4. This longitudinal shift of plates 605 likewise shifts the angle bracket 631 leftwardly, moving all recesses 633 out of register with their overlying studs $85r$. The said studs $85r$ rest then upon the upper edge $631a$ of angle bracket 631 . This acts to lock out all spindles $38r$ in the row r of voting spindles whose studs $85r$ so engage said upper edge $631a$ because guided plates 605 cannot be moved vertically. However, since plates 605 have been shifted longitudinally as described the unvoted of the voting spindles 38 of the said ten horizontal rows are still free to be moved to voting positions. To preclude any operation of these handles 30 of the said spindles 38 for more than the allowed number of candidates in the party D's group, the interlock straps 61 of the voting spindles 38 of said ten horizontal rows are connected in a vote ten condition interlock $42e$. Thus voter having elected to split his ticket among the candidates of the group can operate any ten of the spindles 38 opposite individual names of his party D's group to a voting position but no more than ten.

As a further alternative, the voter may decide to exercise a personal choice option allowed to him under election laws. To this end, strips 635 are secured to the plates 605 . These strips 635 are aligned respectively with the horizontal rows of apertures 607 and extend horizontally and leftwardly as seen in Fig. 5. Each strip 635 is bent laterally at 636 and then again into parallelism at 637 with its body 635 . The edge 638 is provided in parallel portion 637 to lie against the pin $61a$ of the personal choice mechanism in the same horizontal row as that of the apertures 607 with which the strip 635 is aligned.

Since the strips 635 are secured to the plates 605 , disposition of the latter depends on the positions of pins $61a$. As seen in Figs. 5 and 1 with the personal choice slides 140 that are aligned with the spindles 38 which are straddled by plate 605 in unvoted condition, the plate 605 is in the condition of Fig. 2. As soon, however, as the voter moves any one of the aforesaid personal choice slides 140 to an open or write-in voting position, its associated pin $61a$ moves likewise and causes leftward movement of plates 605 to a position similar to that shown in Fig. 4. This acts to lock out all spindles $38r$ in the row r of spindles because of the consequent lateral shift of recesses 633 to the position shown in Fig. 4. The interlock straps 61 of the pins $61a$ are also connected

in the vote ten condition interlock 42e. Thus after having operated any one of the aforesaid personal choice slides 140 to its open or write-in voting position, the voter is privileged to operate either nine more personal choice slides 140, or nine of the voting handles 30 in the said ten rows of spindles 38, or any combination of additional personal choice slides 140 and voting handles 30 to a total not exceeding nine. The total vote cast by him then will be for ten candidates of his own choosing.

The apparatus shown assumes that each group consists of ten so that the interlock portion 42e is set up for a vote ten condition. It is not limited to such a situation, however, and fewer or larger numbers of candidates may appear in a party's group. The interlock 42e can be set up to accommodate any size group required.

The same operations would be available to the voter of party R, he using any one of the voting handles 30r in, for example, vertical columns 4, 5, 6 or 7 for a straight ticket vote of any one of the four groups named by his party, or else the individual voting levers 30 in any of said four vertical columns below the straight ticket row r, or else a combination of such levers 30 and said personal choice slides 140 in the said horizontal rows below to the limit of ten if the interlock portion 42e is set up for a vote ten condition or to any other vote condition to which it may be set up. It is understood, of course, that the angle bracket 630 is long enough to span the columns 4, 5, 6 and 7 and has slots 633 located therein for action with respective of the studs 85r of the butterflies Br in said columns 4, 5, 6 and 7 (see Fig. 2).

It is seen, therefore, under conditions described, the mechanism comprising plates 605, apertures 607, bracket 630, strips 635 and associated parts compel the voter to comply with election laws in voting of the character described.

In an alternative form of construction shown in Figs. 6 and 7, the angle bracket 630 is omitted. Instead the plates 605' which correspond identically with plates 605 are provided with a stud 640. This stud 640 is connected by an interlock strap 61' to a supplemental interlock 42' of identical construction with main interlock 42. This supplemental interlock is set up for a vote one condition. A flange 641 extending laterally rearwardly of the plates 605' and vertically the full width thereof abuts the pins 61a of the personal choice slides alined with the horizontal rows of spindles 38 straddled by plates 605. The biasing spring 642 has its ends 643 and 644 connected respectively to the flange 641 and to the part 15c. This spring functions in the same way as biasing spring 620. The interlock straps 61'r of the studs 85'r of the row r' of spindles are connected to this supplemental interlock 42' in the same vote one portion thereof instead of being connected in the main interlock 42. All other parts of the machine in these Figs. 6 and 7 are identical in construction with parts similarly numbered in various of the other figures and function in the same way. With this modification if the voter moves one of the spindles 38'r in the straight ticket row r' to voting position its interlock strap 61'r acting in the vote one portion of supplemental interlock 42' locks out all others of spindles 38'r and also locks out plates 605' so that none of the individual candidate voting spindles 38 straddled by plates 605' can be actuated. At the same time personal choice slides 140 alined with these straddled spindles cannot

be activated because their pins 61a engage the flange 641 of the locked out plates 605'. If, instead of operating one of the spindles 38'r in the row r' of spindles, he operates one of the personal choice slides alined with the straddled spindles 38 to a write-in voting position, this action causes its pin 61a to shift plate 605' to the left of Figs. 6 and 7. Similar action occurs if he operates one of the straddled spindles 38 to a voting position. This shift acts to lock out all spindles 38'r because interlock strap 61' of the shifted plate 605' is connected to the same vote one portion of the supplemental interlock 42' as the interlock straps 61'r. Thus no straight ticket row of spindles 38'r may be actuated to a voting condition. The voter, however, still remains privileged to operate either nine more personal choice slides 140 or nine of the voting spindles 38 in the ten rows of spindles 38 below the straight ticket row r' of spindles or any combination of additional personal choice slides 140 and spindles 38 of said ten rows to a total not exceeding nine because the main interlock portion 42e in which the interlock straps 61 of these spindles 38 and personal choice slides 140 is set up for a vote ten condition. The vote condition of this portion 42e of the main interlock may be set up for any desired vote condition depending upon the number of candidates that appear in a party's group.

Thus in this modification of Figs. 6 and 7, the mechanism comprising plates 605' and main interlock portion 42e and supplemental interlock 42' and associated parts also compel the voter to comply with election laws in voting of the character described.

It is possible to utilize plates like plates 605 for selective primary elections wherein a voter entering the booth is confined to voting only for candidates of a given party once he has voted for any one candidate of that party. Thus, referring to Fig. 8 and assuming that two political parties are represented at a selective primary election and all the candidates of party D are in selected horizontal rows of two vertical columns of the machine and all the candidates of party R are in selected horizontal rows of two other vertical columns of the machine, two separate plates 605D and 605R (Fig. 8) are provided. These plates are identical in construction with plate 605 except that each plate is designed to span respectively only the vertical columns of the machine containing names of party candidates of one of the two political parties in question. Each of these plates has apertures 607 identical with those of plate 605 for the same purposes and each is supported on the spindles straddled by its apertures in similar manner to plate 605. Each plate 605D and 605R is provided with a stud 650. Each stud 650 is connected by an interlock strap 61' to the supplemental interlock 42' which is set up for a vote one condition. Thus, if a voter operates to a voting position one of the voting spindles 38 in one of the two vertical columns of party D's candidates straddled by plate 605D, this operated spindle 38 acts through the stud 85 on its butterfly B to shift the latter plate to the left of Fig. 8. Because the interlock straps 61' of both plates 605D and 605R are connected to the supplemental interlock 42' which is set up for a vote one condition, the leftward shift of plate 605D locks out or precludes any shift of plate 605R. In consequence, only additional spindles 38 in the columns of party D's candidates can be actuated because the locking out of plate 605R locks out all spindles 38 in the

party R's columns straddled by the apertures of plate 605R. Vice versa, if the first spindle 38 operated by the voter is in the columns of party R's candidates, this action causes its stud 85 to shift plate 605R leftward of Fig. 8 and acts to lock out plate 605D in the same way and thus locks out or precludes voting action of spindles 38 straddled by apertures of plate 605D in the party D's columns of spindles. After a locking out of one of the two plates 605D or 605R is effected as just described, the voter may continue to actuate individual voting spindles 38 in the columns of the party for whose individual candidate he first voted to the limit permitted by the vote condition set up of the main interlock 42 to which the interlock straps 61 of the individual straddled spindles 38 in the party's columns are connected.

If the voter desires to vote a straight ticket, he operates the spindle 38r" in the straight ticket row r" of candidates. The interlock straps 61r" attached to the studs 85r" associated with these spindles are connected in the same vote one portion of the supplemental interlock 42' as the interlock straps 61' which are connected to plates 605R and 605D. The first such spindle 38r" operated causes its associated stud 85r" to enter the underlying slot 633 of and lock out the plate 605R or 605D with which the particular slot 633 is associated. At the same time the interlock strap connected to the stud 85r" that has been actuated moves in relation to the supplemental interlock 42' to lock out movement of the other plate. Thus both plates 605R and 605D are locked out by operation of any of the spindles 38r" in the straight ticket row r" and no individual spindles 38 in either of the party's columns below the straight ticket row r" can be actuated.

In some jurisdictions declared primaries exist wherein the voter prior to entering the booth is required to declare his party affiliation and is allowed to vote only for candidates of the party in which he is enrolled. The plates 605D and 605R are readily adapted for such purpose, it being only necessary as seen in Fig. 9 to provide each with a separate additional stud 651. Each stud 651 is connected to an independent operating member 652. Each operating member 652 extends externally of the machine and is operable independently by an election official. Thus, if a voter is enrolled in the party D, prior to entering the booth, he so declares and the election official operates member 652 connected to plate 605D to cause the plate 605D to shift the left as seen in Fig. 9. Because the interlock straps 61' of plates 605D and 605R are connected to the supplemental interlock 42' which is set up for a vote one condition, the shift of plate 605D to the left by action of the election official acts to lock out plate 605R and thereby prevents the voter from operating voting spindles 38 straddled by apertures of plate 605R in the party R's columns of candidates. Vice versa, if the voter were enrolled in party R the election official would operate member 652 connected to plate 605R to cause it to shift to the left of Fig. 9 and thereby lockout plate 605D and all voting spindles 38 straddled by apertures of that plate 605D so that the voter could then only vote for candidates in the columns of party R. It is understood, of course, that the individual voting spindles 38 are connected to portions of the main interlock 42 by interlock straps 61 in the usual way and that the vote by the voter of individual candidates in

5 the declared party is limited by the vote condition set-up of the main interlock 42 to which the interlock straps 61 of the aperture straddled spindles 38 of the party's candidates are connected.

10 It is to be understood that the individual party plates 605R or 605D are dimensioned to span only as many vertical columns as a party requires. In the embodiments shown in Figs. 8 and 9 each spans two vertical columns. Voting conditions at any particular primary election, however, will determine how many vertical columns and how many selected spindles in horizontal rows in the selected vertical columns are to be straddled by each individual plate 605R or 605D.

15 It is to be understood that if more parties are represented at primary elections, more plates like plates 605D and 605R are required, one such plate being required for each additional party's candidates. All such additional plates would have an interlock strap connecting it to the supplemental interlock 42' set up for a vote one condition so that the movement of any one of the plates in the manner described would lock out all other plates.

20 While specific embodiments of the invention have been described, variations in structural detail within the scope of the claims are possible and are contemplated. There is no intention, therefore, of limitation to the exact details shown and described.

25 What is claimed is:

1. In a voting machine of the character described having a plurality of vertical columns of individual voting spindles, with corresponding spindles in the columns arranged in aligned horizontal rows, mechanism for utilizing selected of the spindles in one of said horizontal rows as straight ticket voting levers for group voting and for utilizing spindles in rows and columns below said one of said horizontal rows for individual voting, said mechanism comprising a plate member straddling selected rows and columns of the spindles below said one of said horizontal rows and having apertures to receive the spindles of the latter named selected rows and columns and a bracket member secured to said plate member, said bracket member having recesses, projecting means carried by each of the spindles for movement therewith upon its movement to a vote indicating position, the said recesses being normally aligned to underlie respective of the projecting means of the said one horizontal row of spindles so that the projecting means of the moved of said spindles may enter the underlying aligned recess and thereby lock said plate member against movement, and said bracket member having a portion engageable with said projecting means of said one horizontal row of spindles when said recesses are misaligned with the latter named projecting means to lock out said spindles in said one horizontal row of spindles, biasing means to maintain the normal alignment of said recesses and respective of the projecting means, and the projecting means of spindles received by apertures of said plate member each normally engaging an edge of the aperture through which a particular spindle is received.

2. A device as per claim 1 in which each said projecting means comprises a butterfly mounted on a spindle and a stud extending from said butterfly.

3. A device as per claim 1 in which each aperture has an arcuate portion normally to receive

one of said projecting means and a straight sided portion adjacent the arcuate position.

4. A device as per claim 1 in which each said recess has a curved portion and a straight sided portion.

5. In a voting machine of the character described having a plurality of vertical columns of individual voting spindles, with corresponding spindles in the columns arranged in aligned horizontal rows, mechanism for utilizing selected of the spindles in one of said horizontal rows as straight ticket voting levers for group voting and for utilizing spindles in rows and columns below said one of said horizontal rows for individual voting, said mechanism comprising a plate member straddling selected rows and columns of the spindles below said one of said horizontal rows and having apertures to receive the spindles of the latter named selected rows and columns, and a bracket member secured to said plate member, said bracket member having recesses, projecting means carried by each of the spindles for movement therewith upon its movement to a vote indicating position, the said recesses being normally aligned to underlie respective of the projecting means of the said one horizontal row of spindles, biasing means to maintain such alignment, and the projecting means of spindles received by apertures of said plate member each normally engaging an edge of the aperture through which a particular spindle is received, each said projecting means comprising a butterfly mounted on a spindle and a stud extending from said butterfly, and each aperture having an arcuate portion normally to receive one of said studs, and a straight sided portion adjacent each arcuate portion, and each said recess having a curved portion and a straight sided portion, and guiding means for said plate member whereby movement of any of the spindles in said one horizontal row of spindles to a voting position will cause the stud of its butterfly to engage in the curved portion of the recess underlying it and lock said plate member in its said normal position thereby precluding operation of selected of the spindles straddled by said plate member, and whereby movement of any of the straddled spindles to a voting position will misalign recesses normally underlying studs of spindles of said one horizontal row of spindles relative to said studs thereby locking out said last-named spindles.

6. In a voting machine of the character described having a plurality of vertical columns of individual voting spindles, with corresponding spindles in the columns arranged in aligned horizontal rows, mechanism for utilizing selected of the spindles in one of said horizontal rows as straight ticket voting levers for group voting and for utilizing spindles in rows and columns below said one of said horizontal rows for individual voting, said mechanism comprising a plate member straddling selected rows and columns of the spindles below said one of said horizontal rows and having apertures to receive the spindles of the latter named selected rows and columns, and a bracket member secured to said plate member, said bracket member having recesses, projecting means carried by each of the spindles for movement therewith upon its movement to a vote indicating position, the said recesses being normally aligned to underlie respective of the projecting means of the said one horizontal row of spindles, biasing means to maintain such alignment, and the projecting means of spindles re-

ceived by apertures of said plate member each normally engaging an edge of the aperture through which a particular spindle is received, said bracket member being an angle bar secured to said plate member and having an upright portion in which said recesses are located, said upright portion being dimensioned to engage the projecting means of the spindles of said one horizontal row and preclude movement of any of such spindles when the said recesses are misaligned with the latter named projecting means.

7. A device as per claim 1 in which said bracket member is an angle bar secured to said plate member and dimensioned to span a plurality of the said vertical columns of spindles, and has an upright portion in which said recesses are located, said recesses corresponding in number to the number of said vertical columns of spindles that are spanned.

20 8. A device as per claim 1 in which said plate member spans all of the said vertical columns of spindles.

9. In a voting machine of the character described having a plurality of vertical columns 25 of individually operable voting spindles, with corresponding spindles of the columns arranged in aligned rows, plate means mounted on selected rows of said spindles and having apertures each to receive a spindle in said selected rows, a multiple vote set-up interlock, interlock straps connecting each of the spindles in the selected rows in said interlock, a one vote set-up interlock, interlock straps directly connecting each of the spindles in the row directly adjacent said selected rows with said last-named interlock, and locking out means associated with said plate means and the individual voting spindles in the row of spindles directly adjacent said selected rows of spindles, said plate means and said locking out means interacting to preclude voting movement of any of the individual voting spindles in said adjacent row when a spindle in said selected rows has been actuated to a voting position, and likewise to preclude voting movement of any of the spindles in said selected rows of spindles when any one of said individual voting spindles in said adjacent row has been actuated to a voting position, said locking out means comprising a member secured to said plate means and having recesses at spaced-apart points, projections carried by the spindles of said adjacent row, said member having an edge engageable with said projections and said recesses being positioned to lie aligned with said recesses to permit the entry of the projections into said recesses upon movement of any of the spindles of the said adjacent row to a voting position, and said edge being engageable with said projections to preclude movement of the spindles of said adjacent row to a voting position when said recesses are misaligned with said projections, the misalignment being effected by movement of any of the spindles in the selected rows of spindles to a voting position.

55 60 65 70 75 10. A device as per claim 9, including personal choice slides aligned with the selected rows of spindles, and wherein said locking out means is also associated with and interacts with those personal choice slides that are aligned with the spindles in the selected rows of spindles to preclude voting movement of any of said individual voting spindles in said adjacent row of spindles when any of the latter named personal choice slides has been operated for vote recording purposes.

11. A device as per claim 10, in which said locking out means comprises interlock straps connecting the personal choice slides alined with the spindles in said selected rows of spindles and also spindles in said selected row of spindles in the multiple vote set-up interlock.

12. In a device of the character described, a plate member having apertures arranged in columns and alined rows, each aperture being generally rectangular in shape and having an arcuate recess in one side wall thereof adjacent its bottom, a bracket member secured to said plate member and extending outwardly of an edge thereof and having an outer rim extending in parallelism with the alined rows, said bracket member having spaced-apart recesses extending inwardly from the rim with one recess alined with each of selected columns of apertures of the plate

10

15

member, and each recess having an arcuate wall and a straight wall with the straight wall extending substantially vertically of said rim.

Certificate of Correction

Patent No. 2,541,553

February 13, 1951

RANSOM F. SHOUP

It is hereby certified that error appears in the printed specification of the above numbered patent requiring correction as follows:

Column 11, line 55, after the word "shift" insert *to*; column 13, line 2, for "position" read *portion*;

and that the said Letters Patent should be read as corrected above, so that the same may conform to the record of the case in the Patent Office.

Signed and sealed this 1st day of May, A. D. 1951.
